SEWING MACHINE ATTACHMENT

George L. Hinman, New Haven, Conn., assignor
to The Greist Manufacturing Company, New
Haven, Conn., a corporation of Connecticut

Application January 2, 1937, Serial No. 118,827

16 Claims. (Cl. 112—160)

This invention relates to sewing machine attachments, and more particularly for an attachment to make what is known as a zigzag or criss-cross stitching operation. In devices for performing an operation of this character, it is necessary that the cloth or material being stitched be moved laterally between each stitching operation, that is, be given a lateral movement each time that the sewing machine needle is raised out of contact with the material. For example, after the needle descends through the material and is again raised, the cloth is given a lateral movement as well as a forward feeding movement, and the needle again descends, making a new stitch laterally and rearwardly of the first. The needle is thereupon raised, and the cloth is given a forward feeding movement and a lateral movement in the opposite direction, so that when the needle descends for the third time the stitch will be in alignment with the first one, thus making a line of zigzag or crisscross stitching upon the material. Such a device has a wide range of usefulness in that it may be employed for a number of different operations. For example, it may be employed merely to make a zigzag line of stitching upon the cloth for decorative purposes, the device being capable of adjustment so that this zigzag stitching may be wide or narrow, depending upon the throw imparted to the cloth in its lateral movements. The device may also be employed to stitch a cord upon a piece of cloth, alternate stitches being made on opposite sides of the cord, so that the latter is stitched firmly to the cloth. Also, it may be used to sew a strip of material such as a band or braid to a piece of material, the device working at the edge of the strip or band and making alternate stitches on and off of the strip, so that the thread is carried over the edge of the strip, thus binding it to the material. Many other uses will suggest themselves, but it is unnecessary to describe them all.

One object of the invention is the provision of a sewing machine attachment for the production of zigzag or crisscross stitching, which will operate efficiently and which will be capable of a variety of uses.

Another object of the invention is the provision of a sewing machine attachment capable of doing crisscross or zigzag work which is capable of a relatively wide range of adjustments for various types of work.

Another object of the invention is the provision of a sewing machine attachment of the character described which will be relatively simple in con-

struction and economical to manufacture, and which will at the same time be efficient in operation and capable of a wide variety of uses.

To these and other ends the invention consists in the novel features and combinations of parts to be hereinafter described and claimed. 5

In the drawing:

Fig. 1 is a side elevational view of a sewing machine attachment embodying my improvements; 10

Fig. 2 is a similar view showing the other side of the device;

Fig. 3 is a top plan view;

Fig. 4 is a partial sectional view on line 4—4 of Fig. 1; 15

Fig. 5 is a fragmentary view partly in section showing one step in the operation of the device;

Fig. 6 is a view similar to Fig. 5, but taken on line 6—6 of Fig. 3;

Fig. 7 is a view similar to Fig. 6 showing the device in inoperative position for performing plain sewing; 20

Fig. 8 is a detail view of the frame member of the device;

Fig. 9 is a view similar to Fig. 8 showing a modified form of attaching means; 25

Fig. 10 is a bottom plan view of the parts shown in Fig. 9;

Fig. 11 is a detail view showing the presser foot and cloth guiding attachment in top plan; and 30

Fig. 12 is a side elevational view of the parts shown in Fig. 11.

To illustrate a preferred embodiment of my invention, I have shown a sewing machine attachment comprising a main frame member having a vertically disposed plate 10 which has at its lower edge a horizontally extending flange 11, this flange being connected to the plate at its front and rear ends, and there being a slot or opening 12 between the plate and flange for the greater part of the length of the latter between the two points of connection. At its forward end the portion 10 of the frame is provided with an attaching foot 13 generally U-shaped in horizontal cross-section, as shown more particularly in Fig. 4. It will be understood that this member is intended to embrace and be secured to the presser bar of an ordinary household sewing machine so that the attachment will be placed in substitution for the usual presser foot. Adjacent the slot or opening 12 the frame member 10 is provided with the stepped surfaces 14 and 15, and it is also provided with an opening or recess 16, which opens into the slot 12. The purpose of these parts will be explained hereinafter. 35 40 45 50 55

Adjacent its upper and rear edge the frame member 10 is provided with an upwardly and rearwardly extending arm 17 having an opening 18 therein for the reception of a pin or rivet 19 upon which is pivotally mounted a fork arm 20 having a bifurcated end 21 designed to embrace the usual screw upon the needle bar of the sewing machine so that the fork arm 20 will be operated about its pivot 19 by the motion of the needle bar.

The fork arm 20 is in the form of a bell crank lever and provided on the side of the pivot 19 opposite the portion 20 with a depending L-shaped arm 22. Adjacent its end this arm is provided with a laterally turned lug 23 adapted to threadedly receive a screw 24 provided with a shoulder 25 and an enlarged adjusting head 26 spaced from this shoulder. The screw 24 is embraced between the shoulder 25 and the head 26 by the arcuately shaped end 27 of a spring, the body 28 of which is secured to the lever portion 22. This spring is tensioned to frictionally engage the screw 24 by means of its curved end 27 and thus hold the screw in an adjusted position.

This curved end of the spring also acts as a stop limiting the adjustment of the screw in the lug 23 by contacting with the head 26 upon one side and the shoulder 25 upon the other, thus determining the limits of adjustment of the screw.

As will be later explained, the adjustment of this screw determines the length of the lateral throw imparted to the cloth so as to determine the width of the zigzag line of stitching.

The frame portion 10 is also provided with an opening 30 adapted to receive a pin or rivet 31 upon which is pivoted the lever 32, this lever having cam portions 33 and 34 upon opposite sides of a high point 35, which cam portions are engaged by the end of the screw 24 to actuate this lever in one direction. The lever is moved in the other direction by a laterally extending lug 36 on the portion 22 of the fork arm 20, so that when the fork arm is reciprocated by the up and down movements of the needle bar, the lever 32 will likewise be oscillated or rocked about its pivot 31.

Pivoted at 37 to the lower end of the lever 32 is a pawl 38, and a cooperating pawl 39 is pivoted to this lever at 40 above the pivot 31. It will be noted that the distance of the pivot of the upper pawl from the pivot of the lever is somewhat greater than that of the lower pawl, so that the upper pawl 39 will have a slightly greater throw than the lower pawl when the lever 32 is rocked.

The pawls 38 and 39 are in the same plane and their adjacent surfaces oppose each other. As shown more particularly in Figs. 5 and 6, the pawl 38 is provided with a notch or recess 41, the front edge of which is slightly cut back or dove-tailed at 42, and this pawl is likewise provided with a recess 43 spaced a slight distance from the recess 41. The upper pawl 39 is likewise provided with recesses 44 and 45 in its lower edge, the recess 44 being slightly cut back or dove-tailed at its rear edge, as shown at 46. The rear edge of the recess 41 and the front edge of the recess 44 may be slightly beveled away from the recess opening, so that when these edges of the recesses encounter the arm of the presser foot, as will be explained later, they will tend to ride thereover, while the opposite will be true of the cut-back or dove-tailed edges 42 and 46, which will tend to grip the arm of the presser foot and impart movement thereto.

As shown more particularly in Figs. 3 and 11,

the attachment is provided with a presser foot 48 which is movably attached to the horizontally disposed frame member 11. For this purpose an L-shaped arm 49 is connected at one side edge of the presser foot 48, and extends rearwardly therefrom, and has a laterally projecting end 50 passing through the slot 12 and pivotally secured to the frame portion 11 by means of the pin or rivet 51. The portion 50 of this arm is designed to be engaged by the pawls 38 and 39, and its front and rear edges may be slightly beveled for this purpose, as shown at 52 and 53, in a manner complementary to the cut-back edges 42 and 46 of the recesses in the pawls.

A lever 54 is pivotally mounted upon the pin 51 and provided with a cam end 55 designed to be swung through the slot 12 and inserted within the recesses 43 and 45 of the pawls. A slotted spring washer 54a may be placed below the head of the pin 51 to frictionally hold the parts in position. Continued movement of this lever will cause it to engage the forward end of these recesses and spread the pawls apart, as shown in Fig. 7, so that neither pawl will engage the laterally extending arm 50 on the presser foot. This holds the pawls in inoperative position so that the presser foot will not be moved, and the sewing machine will perform a plain stitching operation at that time. In other words, this lever is merely to throw the device out of operation when it is not desired to use it, and will save the user the necessity of removing the attachment from the machine whenever a small amount of plain sewing is desired. The inoperative position of this lever is shown in Fig. 3, where the end 55 lies without the plane of the pawls 38 and 39. Its operative position is shown in Fig. 7, in which position the pawls are held out of engagement with the arm of the presser foot. In the position shown in Fig. 7 the forward edge of the cam member 55 lies against the shoulder 15 of the frame member 10, so that the movement of the lever 54 is limited by this shoulder. When the arm 50 stands against the forward edge of the cam member 55 in this position, the presser foot is in an intermediate position suitable for plain sewing. The forward movement of the arm 50 from this position is limited by the shoulder 14, which is the position of the presser foot shown in Fig. 3. While the presser foot in this position has been moved laterally until it is no longer centered with the needle, nevertheless the needle will still pass through the elongated slot 57 in the presser foot. Its movement being thus limited, the presser foot will never be permitted to be placed in a position where the needle might strike a solid portion thereof and be broken.

A spring 58 has its bight portion mounted upon the pivot pin 31, the ends of this spring embracing the outer edges of the pawls 38 and 39. This spring is tensioned to urge the two pawls toward each other, but floats freely upon the pivot 31 so that it has no tendency to hold the pawls in any particular position, that is, the two pawls may be swung upwardly or downwardly to a limited extent without such action being opposed by the spring unless one pawl is moved away from the other.

The presser foot, besides being provided with the elongated needle opening 57, is provided with a longitudinally extending recess or depression 59 in which is designed to be received a cord, for example, when it is desired to use the device. When such an operation is desired, a guide member 60, shown in Fig. 11, is secured upon the 75

presser foot by means of the screw 61 threaded into the opening 62. This guide member also is provided with an opening 63 which receives a small pin or boss 64 on the presser foot, and is additionally provided with a needle opening 65 registering with the needle opening 57 of the presser foot, and a cord opening 66 leading into a groove or recess 67 on the under side of the guide member 60. As shown, this guide member 60 also serves as a cloth guide when it is desired to sew a strip or tape to a piece of material, and for this purpose has a forwardly projecting portion 68 provided with cloth guiding slots 69. The inner edges of these slots are at different positions with respect to the center of the needle openings so as to correctly position the edge of the strip being sewed to the material with respect to the adjusted length of the throw given to the presser foot 48.

The screw 61 is conveniently, permanently but rotatably secured to the guide member 60 by having its shank inserted through a slot 70 in this member, and the edges of this slot slightly closed, so that the screw will be retained therein, but at the same time will be permitted free rotation.

In order that the device may be capable of universal attachment, that is, capable of attachment to sewing machines of various makes, it is necessary to provide attaching portions or adapters of various construction. As shown, for example, in Figs. 9 and 10, the adapter or attaching portion 71 is of a different character from the attachment member 13, shown, for example, in Figs. 1 to 4. This adapter or member 71 is provided with a horizontally slotted member 72 designed to embrace a screw at the lower end of the presser foot. In this case the adapter is provided with a laterally extending body portion 73, which may be secured to the horizontally extending portion 11 of the frame in any desired manner, such as by rivets 74. While the attaching member 13 is shown as formed integrally with the frame, this need not necessarily be done, as it may be made as a separate part and provided with a rearwardly extending portion, which may be secured or riveted to the frame similarly to the construction shown in connection with the member 71. In other words, the frame member 10 and associated parts may be made standard for all machines, and the attaching member or adapter made as a separate part and secured to the attachment according to the particular make of sewing machine with which the attachment is to be used.

The operation of my device may be briefly described as follows: When the parts are in the position shown in Figs. 1, 2, 3 and 6, the fork arm 20 has been raised by the needle bar, and the arm 50 of the presser foot has been thrown forwardly by the upper pawl 39, the under-cut portion 46 of the recess 44 having engaged the arm 50 for this purpose. The presser foot has been moved over into one extreme position, as shown in Fig. 3 and in full lines in Fig. 4, which would move the cloth toward the left of the operator as the latter faces the sewing machine and the attachment.

Upon the succeeding down stroke of the needle bar, the fork arm is moved downwardly, thus making a stitch in the goods and throwing the pawl 39 rearwardly and the pawl 38 forwardly. During this movement it will be noted that both pawls will ride freely over the part 50, owing to the beveled forward end of the recess 44 and the beveled rear end of the recess 41, so that no movement of the presser foot will take place at this

time. When, however, the pawl 38 is moved forwardly to a sufficient extent until the shoulder of the under-cut end 42 of the recess 41 passes the forward edge of the part 50, the pawl 38 will immediately spring upwardly so that the edge 5 of the recess 41 is in operative engagement with the part 50. This upward movement will be brought about by means of the spring 58, which tends to keep the pawls together, as at this time the pawl 39 is riding upon the top of the part 50, 10 and has, therefore, been forced upwardly away from the pawl 38. Upon the next succeeding upward movement of the fork arm 20 as actuated by the needle bar, the pawl 38 will be moved rearwardly and bring with it the part 50, thus swinging 15 the presser foot to the dotted line position shown in Fig. 4, which is the other extreme of its movement. The pawl 39 will have been moved forwardly, but the rear edge of the recess 46 will have been held out of engagement with the part 20-50 by reason of the fact that the forward end of this pawl contacts with the forward end of the pawl 38. This position of the parts is shown in Fig. 5, and it will be seen that the pawl 39 upon this forward stroke has ridden freely over the 25 arm 50. Upon the succeeding down stroke of the fork arm 20, the parts again slide freely over the arm 50, so that no movement is imparted to the presser foot 48, and a stitch is made in the cloth in the position to which it has been moved. 30

Upon the succeeding upstroke of the arm 20, the edge 46 of the recess 44 will drop into engagement with the rear edge of the arm 50, as shown in Fig. 6, and move it forwardly, the engagement

of the forward end of the pawls at this time preventing any upward movement of the lower pawl

35 which might engage the portion 42 thereof with the arm 50. The pawl 38 will upon this up-ward stroke return the presser foot to the position shown in Fig. 3, and the complete cycle of 40 operations has been completed.

It will be seen, therefore, that the cycle of operations is completed after two upward and two downward strokes of the fork arm 20. Upon the downward strokes no movement is imparted to the presser foot 48 to move the cloth laterally, these strokes merely resulting in making a stitching operation through the cloth in the position to which it has been moved. During the upward strokes, however, different operations take place, depending upon whether the arm 50 is in its forward or rear position. When in its rear position the shoulder 46 contacts with the rear side of the arm 50 prior to the engagement thereof by the shoulder 42, and the engagement of the pawls 50 at their front ends will hold the pawl 38 downwardly so that the latter will not engage the arm 50, and this arm will be moved forwardly. When, however, the arm 50 is in its forward position at the beginning of an upward stroke, the shoulder 42 will engage the forward edge of the arm 50 prior to the engagement thereof by the shoul-der 46, and the lower pawl will thereafter hold the upper pawl out of engagement. Therefore, while it might be said that the same motion is 55 given to the pawls 38 and 39 upon each upward stroke of the fork lever 20, the result of these motions is entirely different depending on the position of the arm 50 attached to the presser foot. In one case the lower pawl will engage the arm 60 and move it rearwardly, while in the other case the upper pawl will engage the arm and move it forwardly.

If it is desired to temporarily render the attachment inoperative so that plain sewing may 75

be performed upon the machine, this is done by swinging the lever 54 in a clockwise direction, as shown in Fig. 3, so that the cam end 55 of this lever is inserted between the pawls 38 and 39, as shown in Fig. 7, thus holding both pawls out of engagement with the arm 50. The arm 50 will then be held by the front edge of the cam arm 55 in aligned position for plain sewing, and while the pawls will be moved at each stroke of the needle bar, they will slide idly over the arm 50 and the presser foot will remain at rest.

By adjusting the screw 24 through its threaded connection with the lug 23, the throw given to the lever 32 by the fork arm 20 may be varied as desired in order that the cloth may be given a long or short throw in its lateral movement, and thereby vary the width of the zigzag line of stitching. The slight amount of adjustment shown for this screw is sufficient to vary the width of the line of stitching from an extremely narrow line to a fairly wide one.

When it is desired to sew a cord, for example, or a strip such as a band or tape, upon a piece of material, the guiding attachment 60 is secured to the presser foot, as has been described. This member is rigidly secured in place and will, of course, be moved laterally with the presser foot, so that the strip such as a cord or band will be moved with the goods first in one direction and then in the other. It will be understood that the under surface of the presser foot is knurled or roughened so that it will frictionally engage the material being sewed and effectively move it in a lateral direction.

35. While I have shown and described some preferred embodiments of my invention, it will be understood that it is not to be limited to all of the details shown, but is capable of modification and variation within the spirit of the invention 40 and within the scope of the appended claims.

What I claim is:

1. A sewing machine attachment comprising a frame, a presser foot connected to the frame for back and forth movements in a horizontal plane 45 in a direction generally transverse to the feed of material through the attachment, pawl means adapted to be actuated by the needle bar of the sewing machine to engage a part of said presser foot and effect movement thereof, and means to hold said pawl means in inoperative position.

2. A sewing machine attachment comprising a frame, a presser foot connected to said frame for back and forth movements in a horizontal plane in a direction generally transverse to the feed 55 of material through the attachment, means adapted to be actuated by the needle bar of the sewing machine to effect movement of said presser foot, said means comprising a pawl member engaging a part of said presser foot, and means to prevent such engagement of said pawl member to render the same inoperative.

3. A sewing machine attachment comprising a frame, a presser foot connected to said frame for back and forth movements in a horizontal plane 65 in a direction generally transverse to the feed of material through the attachment, a pair of pawl members carried by said frame, means to effect a back and forth movement of said pawl members, a member attached to said presser foot and adapted to extend between said pawl members to be engaged thereby, whereby said pawl members 70 actuate said presser foot, and means movably carried by said frame and adapted to be moved between said pawl members to hold them

out of engagement with the member attached to the presser foot.

4. A sewing machine attachment comprising a frame, a presser foot pivotally connected to said frame for back and forth movements in a horizontal plane in a direction generally transverse to the feed of material through the attachment, and adapted to bear upon the upper surface of the material, oppositely acting pawls actuated by the needle bar of the sewing machine to engage and effect movement of said presser foot, and strip guiding means attached to said presser foot to be moved thereby.

5. A sewing machine attachment comprising a frame, a presser foot connected to said frame for back and forth movements in a horizontal plane in a direction generally transverse to the feed of material through the attachment, pawl means adapted to be actuated by the needle bar of the sewing machine to effect movement of said presser foot, and strip guiding means attached to said presser foot to be moved thereby, said strip guiding means having an opening therethrough, and said presser foot having a needle opening 20 therein communicating with said first-named opening.

6. A sewing machine attachment comprising a frame, a presser foot connected to said frame for back and forth movements in a direction transverse to the line of travel of the material through the attachment, an oscillating lever mounted on said frame, actuating means for said lever adapted to be operated by the needle bar of the sewing machine, pawl means connected to said lever, means to effect movement of said presser foot 35 by said pawl means, an adjusting screw for varying the movement imparted to said lever, and resilient means to hold said adjusting screw in a predetermined position and limit the adjustment thereof.

7. A sewing machine attachment comprising a frame, means connected to said frame to move the material back and forth in a direction substantially transverse to the line of travel of the material through the attachment, an oscillating lever mounted on the frame, actuating means for said lever adapted to be operated by the needle bar of the sewing machine, pawl means connected to said lever and adapted to effect movement of said first-named means, and an adjusting screw for varying the movement imparted to the 50 lever by said actuating means.

8. A sewing machine attachment comprising a frame, means carried by the frame to move the material back and forth in a direction transverse to the line of travel of the material through the attachment, an oscillating lever mounted on the frame, an arm pivoted to the frame and adapted to be actuated by the needle bar of the sewing machine, means carried by said arm engaging said lever to move the same in opposite directions, and pawl members carried by said lever to engage and move said first-named means.

9. A sewing machine attachment comprising a frame, means carried by the frame to move the material back and forth in a direction transverse to the line of travel of the material through the attachment, an oscillating lever mounted on the frame, an arm pivoted to the frame and adapted to be actuated by the needle bar of the 65 sewing machine, said arm having a lost-motion connection with said lever to move the latter in opposite directions, and pawl members carried by said lever to engage and move said first-named means.

10. A sewing machine attachment comprising a frame, means carried by the frame to move the material back and forth in a direction transverse to the line of travel of the material through the attachment, an oscillating lever mounted on the frame, an arm pivoted to the frame and adapted to be actuated by the needle bar of the sewing machine, said arm having a part engaging said lever to move the same in opposite directions, means to vary said engagement to adjust the throw imparted to said lever by said arm, and pawl members carried by said lever to engage and move said first-named means.

11. A sewing machine attachment comprising a frame, means carried by the frame to move the material back and forth in a direction transverse to the line of travel of the material through the attachment, an oscillating lever mounted on the frame, an arm pivoted to the frame and adapted to be actuated by the needle bar of the sewing machine, said arm carrying abutments to engage said lever on opposite sides thereof to move it in opposite directions, and pawl members carried by said lever to engage and move said first-named means.

12. A sewing machine attachment comprising a frame, means carried by the frame to move the material back and forth in a direction transverse to the line of travel of the material through the attachment, an oscillating lever mounted on the frame, an arm pivoted to the frame and adapted to be actuated by the needle bar of the sewing machine, and said arm carrying abutments to engage said lever on opposite sides thereof to move it in opposite directions, one of said abutments being adjustable to vary the movement imparted to said lever, and pawl members carried by said lever to engage and move said first-named means.

13. A sewing machine attachment comprising a frame, means connected to the frame to move the material back and forth in a direction substantially transverse to the line of travel of the material through the attachment, an oscillating lever mounted on the frame and connected

to said means to move the same, actuating means for said lever adapted to be operated by the needle bar of the sewing machine, means for varying the movement imparted to said lever by said actuating means, and pawl members carried by said lever to engage and move said first-named means.

14. A sewing machine attachment comprising a frame, a presser foot connected to the frame for back and forth movement in a horizontal plane in a direction generally transverse to the feed of the material through the attachment, pawl means adapted to be actuated by the needle bar of the sewing machine to effect movement of said presser foot, and means movable into engagement with said pawl means to render actuation thereof ineffective to move the presser foot.

15. A sewing machine attachment comprising a frame, a presser foot projecting forwardly from the frame and pivotally connected to said frame for back and forth movements in a horizontal plane in a direction generally transverse to the feed of material through the attachment, a pair of pawl members carried by said frame, means to effect a back and forth movement of said pawl members, and a member attached to said presser foot and adapted to extend between said pawl members to be engaged thereby, whereby said pawl members actuate said presser foot, said presser foot being provided with an elongated needle opening through which the material is stitched.

16. A sewing machine attachment comprising a frame, an operating lever attached to the frame and having means for connection to the needle bar of the sewing machine, a presser foot connected to the frame for back and forth movement in a horizontal plane in a direction generally transverse to the feed of the material through the attachment, pawl means actuated by said lever to effect movement of said presser foot, and means movable into engagement with said pawl means to render the same inoperative.

GEORGE L. HINMAN. 45
